UNITED STATES PATENT OFFICE.

WILLIAM HOWLIN, OF NEWTOWN, NEAR SYDNEY, NEW SOUTH WALES, AUSTRALIA.

TIME-CONTROLLED GAS-COCK.

No. 861,854.

Specification of Letters Patent.

Patented July 30, 1907.

Application filed November 18, 1905. Serial No. 288,077.

To all whom it may concern:

Be it known that I, WILLIAM HOWLIN, a subject of the King of Great Britain, residing at 17 Laura street, Newtown, near Sydney, State of New South Wales, 5 Commonwealth of Australia, have invented certain new and useful Improvements in Time-Controlled Gas-Cocks, of which the following is a specification.

This invention relates to time controlled gas cocks and has been devised principally with the view to providing an inexpensive automatic arrangement for opening or closing the taps of gas lamps in which the light of a lamp provided with a pilot or other igniting device may be raised and lowered at predetermined times; while it may be rendered inoperative on moonlight 15 nights or whenever desired.

In describing the invention I will do so with reference to a gas lamp but it will be understood that the same means may be employed for opening or closing taps or valves of any other kind or for operating electric 20 switches and the like.

Referring to the accompanying drawings:—Figure 1 is a view in perspective of the apparatus operated by an ordinary clock of which only those parts are shown which actuate the apparatus. Fig. 2 is a front elevation 25 of the apparatus, the clock or other actuating means not being shown. Fig. 3 is a perspective view illustrating the main operating parts of the apparatus. Fig. 4 is a perspective view of the cams or snails by means of which the apparatus is set in motion at various predetermined times. Figs. 5 and 6 illustrate different positions of the levers, cams and crank disk when the apparatus is in motion. Fig. 7 is a view in perspective illustrating the employment of an electromagnet to actuate the starting lever. Fig. 8 is a perspective 35 view and Fig. 9 a sectional plan on plane 9—9 Fig. 8 illustrating more especially the means employed when it is desired to indicate the time on the clock dial.

The same numerals refer to the same or like parts.

The clock and apparatus are contained within a dust 40 proof casing 8, the clock preferably having instead of the usual dial, a dial 9 provided with twentyfour hour divisions. Mounted on the arbor 10 are sleeves carrying the cams or snails 11 and 12 having respectively the indicating pointers or hands 13 and 14. The clock in 45 addition to its ordinary mechanism (not shown) has a bell crank lever, one arm 15 being in engagement with either of the snails 11 and 12 and the other arm 16 with the starting lever 17.

18 is a spring for supplying motion to the apparatus. 50 The driving wheel 19 imparts its motion through the gear wheels 20^A, 21, 21^A, 22, 22^A, and 23, to the pinion or gear wheel 20. On the spindle 24 of said pinion or gear wheel 20 are secured a cam 25 and a disk 26 provided with a rod 27 connecting to a tap or 55 cock 28. On the spindle 29 of the gear wheel 22 is a cam 30 in which engages one arm 31 of a bell crank le-

ver the other arm 32 engaging with the cam 25. The cam 30 has a lug 33 with which engages a lever 36 operated by the handle 37. On the gear wheel 22 is a lug 35 which engages with a pawl 34. The spring 18 of the 60 apparatus is wound by turning the spindle 38 on the end of which is a gear wheel 39 gearing with the wheel 40 mounted on the spindle 41 of the driving wheel 19.

In Figs. 8 and 9 on the arbor 10 is a pinion 49 gearing with the wheel 50 of pinion 51 thereby making the two 65 wheels 47 and 48 to move simultaneously with the snails 11 and 12. These snails are sufficiently loose to allow them to be moved independently of the wheels 47 and 48 when it is desired to alter the hours of lighting or extinguishing. Also the indicators or hands 13 and 70 14 on the sleeves of the snails 11 and 12 are sufficiently loose to be moved independently of the snails. On these sleeves are also the notched disks 52 and 53 which are moved by suitable keys engaging in the notches so as to alter the positions of the cams when desired. After 75 the mechanism has been set to operate at the required times the two hands 13 and 14 are placed one over the other, thereby appearing as one hand, when viewed from the front, and act as an hour indicator. On the arbor 10 is the minute hand 46.

80 The following is the operation of the apparatus. The clock and apparatus each having been wound the snails 11 and 12 are set respectively to the hours for lighting and extinguishing or raising and lowering the light. No more attention is necessary except every eight days 85 (when an eight day clock is used) for re-winding, and when the hours for raising and lowering the light are to be altered. When the end of the arm 15 of the bell crank has almost been reached by the edge or point of the cam 11 and the arm 16 having meanwhile pulled 90 the levers 17 and 32 into the position shown in Fig. 5, the cam 30 has made a quarter revolution but is held there by the lug 35 engaging with the pawl 34. On the arm 15 passing over the edge of the cam 11 the bell crank lever resumes its normal position, allowing also 95 lever 17—through the agency of the spring 42—to fall into the position shown in Fig. 6. Then the pawl 34 disengages with lug 35 and allows the mechanism of the apparatus to continue its motion and in order to do so the cam 25 by means of arm 32 prevents the arm 31 engaging with the cam 30 until the disk 26 has made a half revolution. The arm 31 then engages with the cam 30 (the lever 32 having resumed its normal position as shown in Fig. 2) thus permitting the disk to make only half revolutions at a time, each half revolution either 100 turning on or off the tap.

The cam 30 has a rabbet or recess 45 so that the arm 31 may engage with it and thereby prevent the mechanism being accidentally set in motion when winding the spring 18.

105 In the event of the light not being required (as for instance on several successive moonlight nights) the

handle 37 is moved so that the lever 36 engages with the lug 33 on the cam 30 thus preventing the mechanism of the apparatus being set in motion but at the same time allowing the clock to continue its movement.

5 Instead of clock mechanism, an electromagnet 43 may be used to actuate the starting lever 17, the latter being provided with an armature 44 (Fig. 7). In this arrangement the necessary current to energize the magnet may be controlled from a central station.

10 In turning off or lowering the light the arm 15 is actuated by the snail 12 and the same movement is repeated to turn the disk 26 half a revolution.

Having now described my invention, what I claim as new and desire to secure by Letters Patent is:—

15 1. In an apparatus of the class described, the combination of a cam, an arm for engaging said cam, a second cam, a second arm for engaging the second cam and movable with the first arm, a lever, spring-operated in one direction, a clock, mechanism actuated by the clock for moving the lever in opposition to the spring and to cause said lever to disengage said arms from the cams, a detent movable with the lever for temporarily preventing the rotation of said first cam, the second cam serving to operate against the second arm on the rotation thereof to hold the first arm in an inoperative position during a predetermined period of rotation of the second cam, and means for rotating the two cams.

20 2. In an apparatus of the class described, the combination of a cam, an arm for engaging said cam, a second cam, a second arm for engaging the second cam and movable with the first arm, a lever, spring-operated in one direction, a clock, mechanism actuated by the clock for moving the lever in opposition to the spring and to cause said lever to disengage said arm from the cams, a detent movable with the lever for temporarily preventing the rotation of said first cam, the second cam serving to operate against the second arm on the rotation thereof to hold the first arm in an inoperative position during a predetermined period of rotation of the second cam, means for rotating the two cams, and manually operable means for engaging the first cam to prevent rotation thereof.

25 3. In an apparatus of the class described, the combination of a cam, an arm for engaging said cam, a second cam, a second arm for engaging the second cam and mov-

able with the first arm, a lever, spring-operated in one direction, a clock, independently-adjustable cams actuated by the clock and each adapted to move said lever in opposition to the spring and to cause said lever to disengage said arms from the cams, a detent movable with the lever for temporarily preventing the rotation of said first cam, the second cam serving to operate against the second arm on the rotation thereof to hold the first arm in an inoperative position during a predetermined period of rotation of the second cam, and means for rotating the first two cams.

50 4. In an apparatus of the class described, the combination of a cam, an arm for engaging said cam, a second cam, a second arm for engaging the second cam and movable with the first arm, a lever, spring-operated in one direction, a clock, independently-adjustable cams actuated by the clock and each adapted to move said lever in opposition to the spring and to cause said lever to disengage said arms from the cams, a detent movable with the lever for temporarily preventing the rotation of said first cam, the second cam serving to operate against the second arm on the rotation thereof to hold the first arm in an inoperative position during a predetermined period of rotation of the second cam, a spring motor for rotating the first two cams, and notched disks for adjusting said independently-adjustable cams relatively to each other for varying their time of actuating said lever.

55 5. The combination of a train of gears, a spring for turning one of the gears and thereby the other gears, a cam concentric with one of the gears, an arm to normally prevent turning of the cam, a second cam, a second arm co-operative with the second cam, a lever, spring operated in one direction, a detent movable with the lever and adapted when said lever is tripped to prevent turning motion of the first cam, and the second cam when turned serving to operate against the second arm to hold the first arm in an ineffective position, a second lever acting against the first lever, and clock mechanism to move the second lever in a direction to operate the first lever and thereby release the two cams.

60 In testimony whereof I have hereunto set my hand in presence of two subscribing witnesses.

WILLIAM HOWLIN.

CHARLES EDWARD GRAHAM,
HENRY WATCHORNE CLARKE.
